RAILWAY COUPLER OPERATING ROD MOUNTING ARRANGEMENT

Frank H. Kayler, Alliance, Ohio, assignor to American Steel Foundries, Chicago, Ill., a corporation of New Jersey

Filed Sept. 13, 1957, Ser. No. 683,875

5 Claims. (Cl. 213—171)

This invention relates to couplers and more particularly to an improved operating mechanism for an automatic railway car coupler.

The invention comprehends an improved coupler operating rod and mounting bracket arrangement for use with a rotary operated type coupler.

As is known to those familiar with the coupler art, many of the present day automatic couplers, such as the A.A.R. Alternate Standard Type F coupler, are of the vertically interlocking type whereby if one of a pair of mated couplers is pulled out of or separated from its related railway car, it can be supported by the other coupler so that it cannot fall onto the track or roadbed and cause a derailment or other serious accident.

Even with couplers having the vertical interlock feature, however, in order for one coupler to support another, it is essential that the couplers remain coupled to each other when a pull out occurs, because when a coupler pulls out or separates from its related car, it tends to exert tension and torsion forces on the operating rod causing the rod to rotate and unlock the coupler, thereby resulting in the undesired separation or uncoupling of the couplers.

Additionally, the forces exerted on an operating rod by the pull out of a related coupler tend to deform the rod as well as the bracket which supports the handle end of the operating rod from the railway car.

Accordingly, it is a primary object of this invention to provide, in an automatic rotary operated railway car coupler, an operating mechanism adapted to prevent the accidental uncoupling of mated couplers in the event of a pull out or separation of one of the couplers from its related car.

It is another object of the invention to provide a coupler operating rod mounting arrangement wherein the pull out or separation of a coupler from a car will not result in the application of stresses on the operating rod and mounting bracket causing damage thereto.

A more specific object of the invention is the provision of a coupler operating rod and mounting bracket arrangement wherein the end of the rod is readily detachable from the bracket and can freely withdraw from the bracket in the event a pulling force in an inboard direction is exerted on the rod.

Another more specific object of the invention is the provision of a coupler operating rod and mounting bracket arrangement wherein the outboard end of the rod is free to angle within the bracket to prevent the bracket from being pulled off the car or damaged when outside forces applied to the operating rod cause it to angle laterally.

These and other objects of the invention will be apparent from an examination of the following description and drawings, wherein:

Figure 1 is a fragmentary top plan view of a portion of one end of a railway car to which has been applied a coupler and coupler operating mechanism embodying features of my invention;

2

Figure 2 is a front elevation view of the structure illustrated in Figure 1;

Figure 3 is a side elevation view of a portion of the structure illustrated in Figures 1 and 2;

5 Figure 4 is a view similar to Figure 1, but with the coupler shown in a pulled out condition;

Figure 5 is a view similar to Figure 4, but showing only the rod and bracket with the rod pulled completely out of the bracket, and

10 Figures 6, 7, and 8 are top plan, front elevation, and side elevation views, respectively, of an operating rod mounting bracket embodying a modified form of my invention.

It will be understood that certain elements have been 15 intentionally omitted from some views where they are believed to be illustrated to better advantage in other views.

Referring now to the drawings for a better understanding of the invention, it will be seen that a vertically interlocking coupler indicated generally at 10 having a conventional rotary operated locking and unlocking mechanism of the type similar to that disclosed in Patent No. 2,160,419 issued to E. P. Kinne et al. on May 30, 1939, is shown as being pivotally connected by a pin 12 to the draft gear mechanism (not shown) of a railway car 14. The structural details of the connection are not shown inasmuch as they do not form an essential feature of this invention.

As best seen in Figures 1 and 2, the rotor 16 of the 30 coupler lock operating mechanism (not shown) includes an eye portion 18 which receives and is engaged by a hook portion 20 formed on the inboard end of a transversely extending operating rod 22.

The outboard end of the rod 22 is supported for rotational movement within a mounting bracket 24 which may be fixed to the end of the car body in any desired manner, such as by means of nut and bolt assemblies or rivets 26 which connect a base flange 28 of the bracket to a support plate 30 rigidly secured to the end of the car.

The bracket 24, in addition to comprising a base flange 28, includes a forwardly extending operating rod receiving socket 32 which is generally U-shaped as seen from the side and presents an operating rod receiving slot 34 defined by spaced vertically extending front and rear lugs 36 and 38, respectively. As best seen in Figures 1 and 6, the rod socket 32 is spaced forwardly from the base flange 28 a sufficient distance to prevent any portion of the rod from contacting the base flange in the event of angling of the rod. Additionally, the bracket 24 is 45 provided with a stop flange 40 extending downwardly from the socket 32 and presenting a forwardly facing preferably crowned vertical abutment surface 40a which is disposed forwardly of the rearward portion of the socket an amount approximately equal to the diameter 50 of the rod or, in other words, is located directly below, and in vertical alignment with, the forward face of an operating rod as it normally lies in the socket. The purpose of this stop flange 40 will be described hereinafter in the specification.

60 As best seen in Figures 1 and 6 the inboard or right half of rear lug 38 and the outboard or left half of front lug 36 present parallel vertical surfaces 38r and 36l, respectively, which define the limits of movement of the outboard end of the rod within the slot 34, as the in-

65 board end of the operating rod is moved rearwardly towards the car, and which lie in parallel planes extending approximately transversely of the car. Also, the outboard or left half of rear lug 38 and the inboard or right half of front lug 36 present surfaces 38l and 36r, respectively, which define the limits of movement of the out-

70 board end of the rod in slot 34, as the inboard end of the rod is moved forwardly away from the car, and which

lie in parallel planes disposed at an angle of approximately 30° relative to the first-mentioned pair of slot surfaces. The purpose of this angularity will be hereinafter described in the specification.

Still referring to Figures 1 and 2, it will be seen that the rod 22 comprises an elongated center portion 42 with the previously mentioned hook 20 formed on the inboard end thereof and with a generally straight transversely extending shaft 44 formed on the outboard end thereof. In its normal position, the rod is mounted with hook 20 disposed to extend through the coupler rotor eye 18 and with shaft 44 disposed within the slot 34 of mounting bracket 24. The shaft may be prevented from moving up and out of the slot by means of a filler 70 retained in the slot 34 over the shaft by a pin or cotter 72 extending through the lugs 36 and 38. It is to be understood that the shaft 44 must be long enough to extend outboardly of socket 32 a sufficient distance to accommodate horizontal angling of the coupler, so that in no operative position of the coupler will the rod be pulled out of the socket.

Additionally, rod 22 comprises a handle portion 46 which includes a relatively short upper element 48 parallel to the shaft 44 and rigidly secured thereto as by welds 49 at a point inboardly of the mounting bracket 24.

The handle portion 46 also includes a relatively short generally vertical element 52 integral with the element 48 and having extending outboardly therefrom a preferably integrally formed stop element 54 which is spaced vertically below the shaft 44. Depending from the outboard end of stop element 54 is a generally vertically extending hand grip member 56 having an inturned grip or handhold element 58 formed on the lower extremity thereof. The exact details of the handle portion of the rod are not essential to the invention except for the stop element 54 which is spaced from and preferably parallel to shaft 44.

Although the force required to move the coupler locking mechanism is great enough to prevent the free swinging of the rod handle in a forward direction from unlocking the coupler, it is also desirable to prevent unnecessary swinging of the handle in the rearward direction, and for this reason stop flange 40 has been provided.

In order for the stop flange 40 to be effective, however, in accomplishing its function of preventing free swinging of the operating rod handle, the surface 40a is crowned so that engagement between it and rod stop element 54 is preferably line rather than surface contact, and it is also preferable that the surface be located directly below and in vertical alignment with the forward face of the rod shaft 44 as it normally lies in the socket 32, or in other words, located rearwardly adjacent the rear surface of the rod stop element 54 as the rod handle 46 hangs in its normal position. The location and shape of surface 40a are especially important in the event of a pull out of the coupler from the car body, for at that time as the coupler moves forwardly from the car it carries with it the inboard end of the rod, with the result that the rod tends to rotate about a vertical pivotal axis defined by the line of contact between the outboard end of the rod and the bracket stop flange. With the surface 40 being crowned and disposed below the forward face of the portion of the rod shaft in the socket, the rod is free to pivot in a horizontal plane about the above-mentioned vertical pivotal axis. If, however, as in prior art arrangements, the stop surface corresponding in function to surface 40a were located outboardly of the socket the rod would not be free to pivot about a vertical axis, because the rod would be in contact with the bracket at two places, at the socket and at the stop flange, with the result that a camming action could take place between the rod stop element 54 and the stop flange surface causing the rod to rotate in a counterclockwise direction, as seen from the outboard end, about its generally horizontally extending longitudinal axis and thereby unlock the coupler.

Now referring to Figure 4 of the drawings, it will be seen that when the coupler 10 is pulled out or separated

from the car 14, the operating rod 22 tends to angle with respect to the mounting bracket 24. As described above, because of the angularity of the bracket slot surfaces, shaft 44 of rod 22 is free to angle forwardly within the slot to a limited degree thus preventing the rod and/or bracket from bending and also preventing the bracket from being torn from the railway car.

Additionally, as best seen in Figures 2 and 5, if the coupler pulls out or separates from the car causing the rod to angle and move in inboard direction, shaft portion 44 is entirely free to withdraw from or pull out of the bracket slot 34. This free rod pull out feature also insures that no damage will be caused to the rod or to the bracket by reason of a force being exerted on the rod in an inboard direction by the coupler as it pulls out.

A third important safety feature of the invention is best understood by reference to Figure 2 of the drawings where it will be seen that in the event of any angular movement of the rod, the stop element 54 of the handle portion 46 can engage the crowned forward vertical surface 40a of stop flange 40 on a vertical line and pivot freely about a vertical axis without any danger of camming action taking place between the rod and bracket which would tend to turn the rod and rotor and unlock the couplers, causing them to separate and fall onto the track or roadbed.

Referring now to Figures 6, 7, and 8 of the drawings, wherein is illustrated a modified form of the invention, it will be seen that the mounting bracket 24a is similar to that previously described in connection with the first-mentioned embodiment except that in addition to having a stop flange 40 with a vertical surface 40a, it is provided with an additional stop flange 41 presenting a transversely extending vertical surface 41a. The purpose of the additional surface 41a is to permit the use of the bracket with a standard operating rod of the type used for many years and which has only a vertical handle portion depending from the shaft, without the stop element 54 of my novel operating rod. In the event this type of rod has to be used, engagement with the surface 41a and the rear face of the vertical portion of a rod handle will serve to prevent free swing of the handle.

As best seen in Figure 6, the surface 41a is located rearwardly of surface 40a a distance equal to the diameter of the rod, or in other words, is in substantially the same vertical plane as the rear ends of the socket slot 34. The reason for this is that in this standard rod the handle portion is not offset from a shaft, as in the case of my novel rod.

I claim:

1. In an operating rod mounting arrangement for a railway car having an automatic coupler, a generally U-shaped mounting bracket secured to one end of the car inboardly adjacent one side thereof, and an operating rod having its inboard end connected to the coupler for operation thereof and having its outboard end supported by said bracket, said outboard end of the rod comprising a generally straight horizontally extending shaft cradled for limited rotative movement in said bracket and an integral handle member extending from said shaft at a place inboardly of said bracket, said handle member comprising a horizontally extending stop bar element spaced from and extending below said shaft and a handhold element extending from the outboard end of said stop bar element, said bracket including a rod socket comprising spaced lugs defining a horizontal slot in which is rotatably received the shaft of said rod, and a vertically extending stop flange depending from and disposed directly below said socket for engagement with the stop bar element of the rod to limit rotation of the rod in a clockwise direction as seen from the outboard end of the rod, the slot of said socket being open at both ends and being wider at said ends than in the center to accommodate angling movement of the shaft therein fore and aft of the car and to permit free withdrawal of said shaft there-

from by movement of the shaft forwardly and inboardly of the car during pull out of the coupler.

2. In a coupler operating rod mounting arrangement for a railway car having a coupler, the combination with said car and coupler of: a mounting bracket secured to one end of the car inboardly adjacent one side of the car, said bracket including a pair of upstanding lugs spaced from each other to define threebetween a transverse horizontal slot open at its ends and wider at said ends than at its center, and a vertically extending stop flange disposed directly below said opening; and an operating rod connected at its inboard end to the coupler, the outboard end of said rod comprising a generally straight horizontal shaft disposed to extend through the slot of said bracket for limited rotative movement therein, and an integral handle depending from said shaft, said handle having a vertical portion secured to said shaft at a point located inboardly of the bracket and a horizontal stop element extending outboardly from said vertical portion and located below said shaft for engagement with said stop flange to limit rotation of the rod in a clockwise direction as seen from the outboard end of the rod.

3. In a coupler operating rod mounting arrangement for a railway car having a coupler, the combination of: a bracket mounted on an end of the car at one side thereof, said bracket including a socket having a horizontal opening extending transversely therethrough, and also including a stop flange presenting a vertical abutment surface located below and in substantial vertical alignment with the opening of said socket; and an operating rod extending generally transversely of the car with its inboard end connected to the coupler and with its outboard end supported by the bracket, the outboard end of said rod including a generally straight shaft extending horizontally through the opening of said rod socket and an

integral handle joined to said shaft at a place located inboardly of the bracket, said handle including a generally horizontal portion spaced vertically below said shaft and disposed for engagement with the stop flange of the bracket to limit the rotation of the rod in a clockwise direction as seen from the outboard end of the rod.

4. A mounting bracket according to claim 3, wherein said stop flange surface is crowned about a vertical axis.

5. In a coupler operating rod mounting arrangement for a railway car having a coupler, the combination of: a support bracket mounted on an end of the car at one side thereof, an operating rod having its inboard end connected to the coupler and having its outboard end supported by the bracket, said outboard end comprising a generally straight horizontal shaft disposed to extend transversely of the bracket through a horizontal opening presented by the bracket, said rod including an integral handle offset from said shaft and joined to the shaft at a place located inboardly of said opening so that the shaft can be freely withdrawn from said opening by the axial movement of the rod in an inboard direction a predetermined distance, said handle including a portion disposed for engagement with an abutment surface presented by the bracket located directly below and a vertical alignment with said opening to limit rotation of the rod about its longitudinal axis in a clockwise direction as seen from the outboard end of the rod.
